 Attorney, Agent, or Firm—Thomas H. Murray; Clifford A. Poff

[21] Appl. No.: 234,889

[57] CLAIM

[22] Filed: Feb. 17, 1981

The ornamental design for a packaging container, as shown and described.

DESCRIPTION

[51] Int. Cl. .... D9—03
 [52] U.S. Cl. D9/312; D9/313
 [58] Field of Search 229/8; D9/312, 313, D9/432, 431, 334

The FIGURE is a perspective view of a packaging container showing my new design. The sides not shown are the same in appearance as the sides shown and the bottom is plain and unornamented.
